UNITED STATES PATENT OFFICE.

JESSE B. CURL, OF DES MOINES, IOWA, ASSIGNOR OF ONE-HALF TO ALFRED ANDERSON, OF SAME PLACE.

VAPOR-BURNING STOVE.

SPECIFICATION forming part of Letters Patent No. 410,537, dated September 3, 1889.

Application filed May 13, 1889. Serial No. 310,675. (No model.)

To all whom it may concern:

Be it known that I, JESSE B. CURL, a citizen of the United States of America, and a resident of Des Moines, in the county of Polk and State of Iowa, have invented an improved Vapor Generator and Burner, of which the following is a specification.

My object is to provide a vapor-burning attachment that is adapted to be applied to stoves of common form in such a manner that it can be readily operated, with economy and safety, by any person of ordinary intelligence for the purpose of cooking and all the common uses of a stove.

15 My invention consists in the construction and combination of a vapor-generator and one or more vapor-burners with a stove, as hereinafter set forth, pointed out in my claims, and illustrated in the accompanying drawings, in which—

Figure 1 is a top view of my vapor-generator from which the top side or cover is removed. Fig. 2 is a vertical sectional view through the longitudinal center of the vapor-generator, as indicated by the dotted line in Fig. 1. Fig. 3 represents a section of one of my burners that has been divided at its vertical center. Fig. 4 shows my complete invention applied to a stove as required for practical use. Fig. 5 is a top view showing two burners combined in such a manner that the burners can be operated independently whenever desired. Fig. 6 is a side view of the same two burners and the tubes that connect them and a solid deflector that projects over the tops of the burners. Fig. 7 is a sectional view of the tube and burner connecting device, located midway between the two burners in Fig. 6.

40 *a* and *b* are the flat parallel walls and top and bottom of my oil-receptacle and vapor-generator cast complete in one piece. It may vary in depth and length, as desired. Its end portions are preferably circular in shape and broader than the central portion and terminate in tubular screw-threaded sockets *c*, adapted to receive a plug *d* at one end and the tube *f* at the other end, to be thereby connected with an elevated reservoir in a common way.

45 *g* is an integral elbow-shaped partition in

the interior that extends from the center portion to near one end in such a manner that oil introduced through the tube *f* at one end will flow to the other end to pass around the end of the partition, and then backward to an opening *h* in the central portion of the bottom *b*.

55 *m* is a screw-threaded socket extending outward to receive the end of a tube.

n is the main portion of my burner, made 60 of iron by casting in a mold. It has an open flaring top *n'* and parallel integral open-ended tubes *n''*, that extend downward from its sides to convey air to the combustion-chamber at their open top ends.

65 *n'''* is an integral tube in a horizontal position, that has one end open and screw-threaded, and adapted to receive the end of a tube *r*. A perforation in the top of the tube *n'''* allows oil and vapor to escape into the 70 combustion-chamber and perforations in the bottom of the combustion-chamber, and on the opposite sides of the horizontal tube allow oil to escape and to drop down upon an absorbent material, where it can be set on fire 75 to start the generation of vapor in the burner, and also in the generator above the burner, by means of a T-coupling, as shown in Fig. 4, in such a manner that oil and vapor can be thereby conveyed and distributed to the burners. 80 *s* in Fig. 4 is a tube connected with the T-coupling and the vapor-generator, as required to support the generator.

85 In place of the T-coupling the device shown in Figs. 5, 6, and 7 may be advantageously substituted. It is tubular and has two distinct chambers *s'* and *s''*, so that separate tubes may be connected therewith and each burner operated independently of the other whenever desired.

90 *s'''* is an integral vertical projection adapted to support a solid plate *a'* in place of the vapor-generator. A stud on the top of the projection enters a corresponding perforation in the center of the plate and detachably connects the two parts. When the plate is used in place of the vapor-generator, the heat generated by the burners will be deflected and distributed by the plate, and the chambers *s'* 95 will serve as vapor-generators.

y represents a metal plate fitted in a stove and supported above the grate. It has openings through which the air-conveying tubes *n''* of the burner extend downward. Lugs or 5 projections on the tubes, as indicated by dotted lines in Fig. 3, will engage the plate and retain the burners and generator combined at a proper elevation within the stove, as required to utilize the heat generated by the 10 burners, where pots and kettles can be placed in and over the openings in the top plate of the stove.

z (shown in Fig. 4) represents a check-valve connected with the tube *f* to arrest the flow 15 of oil from a reservoir at the top of the tube.

To start a fire as required in the practical use of my invention thus combined with a stove, it is only necessary to open the valve to allow oil to flow through the generator and 20 the burner to drip upon the plate *y* in the stove, or upon asbestos or other suitable material placed upon the plate and around the tubes *n''*, so that it can be lighted with a match. As soon as the burning oil heats the 25 burners and generator, the oil therein will be converted into vapor and the vapor will burn at the tops of the burners and continue to produce vapor in the generator at the same time that the heat is utilized at the top of the 30 stove for cooking.

To stop the operation, it is only necessary to close the valve in the tube *f* to arrest the flow of oil.

I am aware vapor-burners have had openings in their bottoms to admit air; but my 35 manner of forming a burner complete in one piece and combining it with a generator and a deflector and a stove is novel and greatly advantageous.

I am also aware that burners have been 40 cast complete in one piece; but my peculiar form of burner and my manner of combining two burners with a coupling device and deflector and a perforated plate in a stove are 45 novel and greatly advantageous in convert-

ing a cook-stove that has a grate for burning coal into a vapor-burning stove.

I claim as my invention—

1. A vapor-burner cast complete in one piece, comprising a hollow metal case or combustion-chamber having a contracted neck and flaring open top at its center, open-ended tubes at its outside extending downward, an integral tube extending across the bottom and open at one end to be connected with an extraneous tube, a perforation in the top of said horizontal tube, and one or more perforations in the bottom of the case at the side of said horizontal tube, substantially as and for the purposes stated. 50 55

2. A vapor generator and burner coupling device cast complete in one piece and provided with two distinct chambers and two openings in each chamber to admit tubes, and an integral post adapted to support a deflector, 60 in combination with two burners and a deflector, for the purposes stated. 65

3. The combination of a generator having a post adapted to support a deflector, two burners and tubes extending therefrom into distinct chambers in the generator, and a deflector extending horizontally over the tops of the burners, in the manner set forth, for the 70 purposes stated.

4. The vapor-burners *n*, having open tops 75 *n'*, open-ended tubes *n''*, and perforated tubes *n'''*, a generator *s*, having chambers *s'* and *s''*, and an integral post *s'''*, a deflector on said post extending horizontally over said burners, arranged and combined substantially as shown 80 and described, for the purposes stated.

5. A burner *n*, having tubes *n''*, a plate *y*, having perforations to admit said tubes, a vapor-generator, and flame-deflector arranged and combined with a stove, in the manner set 85 forth, for the purposes stated.

JESSE B. CURL.
